[57] ABSTRACT

A conveying apparatus, particularly for transferring cardboard boxes from a storage magazine, in which the boxes are stored the ones against the others in a laid flat condition, to a receiving surface, the boxes possibly undergoing a processing step in an intermediate station, comprising means adapted to draw the boxes from said magazine and to give them the final parallelepipedal shape, two parallel conveying members, more particularly two endless chains, each member having affixed thereto a plurality of spaced non aligned positioning and retaining elements, whereby box receiving spaces are defined by the two parallel members and by a positioning and retaining element on each said member, drive means adapted to independently and adjustably drive the said members in a preselected direction, so that the boxes being charged by said first mentioned means are carried away from the storage magazine towards the intermediate processing station and then towards the receiving surface, the distance of the two positioning elements defining a box receiving space being adjusted to the box size by suitably adjusting the drive means, and means downstream of the processing station adapted to engage and controllably guide the cardboard boxes for their discharge on the receiving surface.

Fig. 2

Fig. 4**Fig. 3****Fig. 6****Fig. 5**Fig. 8Fig. 7**Fig. 10****Fig. 9**## CARDBOARD BOX CONVEYOR

This invention relates to a conveyor adapted to draw card-board boxes from a magazine and to convey it to one or more processing stations.

More exactly, the invention relates to a conveyor which is particularly adapted to be used with cardboard boxes intended to have a parallelepipedal final shape and which are stored flat one against the other with the sidewall closed and with the end flaps open. These boxes should be drawn from a magazine and arranged onto the conveyor, one after the other, already open in their final parallelepipedal shape to be subjected to processing in the already cited station.

The conventional conveyors, which can be equipped with means for a continuous or intermittent motion, usually comprise a flexible member which is rotated in a closed loop, such as for example a couple of chains, on which there are affixed box positioning and retaining members. These positioning and retaining members for the boxes are arranged properly spaced apart so as to define therebetween a seating on which each box as drawn from the magazine must be located.

Such a seating has a length equal to the thickness of each box and is so made as exactly to define the plan space requirement for a box, the latter being thus retained in a preselected position.

The conveyors thus made up have the drawback that each seating has a mouth opening for the boxes which is extremely precise so that the movement of the device which draws the boxes from the magazine and inserts them, open, into the above mentioned seating must be exactly attuned with the movement of the conveyor: an even slightest phase defect is such as to cause the boxes not to enter the seating on the conveyor in the correct way, thus giving rise to a deformation of the box or a stoppage in the production cycle. Due to the ever increasing rotation speeds as required for the conveyor, it has become extremely difficult to synchronize the movement of the device which draws the boxes from the magazine with the movement of the conveyors as embodied according to the conventional techniques.

Another drawback as experienced with the conventional conveyors is that, whenever the box shape is changed, it becomes necessary to change the gap between the positioning and retaining members which define the seating for the boxes, and they should be individually dismantled from the chains: this fact requires the stoppage of the production run during a comparatively lengthy period of time, the economical disadvantages being apparent.

A principal object of the invention is to provide a cardboard box conveyor adapted to operate at a high speed in a perfect attunement with the device which draws the boxes from the magazine.

Another object of the invention is to provide a cardboard box conveyor of the kind referred to above which can be adapted in a simple and quick manner to different shapes of boxes.

Yet another object of the present invention is to provide a cardboard box conveyor which is provided in correspondence with the outlet end with a device which is adapted automatically to eject the boxes so as to place them onto another conveyor.

In view of the objects as enumerated above for this invention it has been envisaged to provide a cardboard box conveyor of the kind referred to above, which is

characterized in that it comprises at least a flexible member as controlled to be rotated in a closed loop so as to define two laps which are parallel to one another and are spaced apart through a distance equal to the width of the boxes, a plurality of retaining members appropriately affixed and spaced apart from each other on said flexible member, a motive means adapted to cause said flexible member to be rotated so that said parallel laps may be advanced in concordant directions and synchronously with respect to each other, and that the retaining members on a lap are staggered through the thickness of a box with respect to the retaining members on the other lap so as to define a plurality of couples confronting shoulders which are adapted to receive, between them, the boxes which abut each couple of shoulders in correspondence with two diagonally opposite edges of said boxes.

In a preferred embodiment of the invention said parallel laps are defined by two chains which can be controlled so as to be rotated in a closed loop by a single motive means which is positively connected thereto through a drive transfer member.

The conveyor according to the invention can also be equipped, at the box outlet end, with a device adapted automatically to eject each box and to position it previously between the retaining members of another conveyor which is arranged perpendicularly to the former conveyor. Said device comprises a couple of rings which are rotated in opposite directions and are each equipped with a plurality of fingers which are extended radially and are spaced apart from each other in an even manner, the fingers of one ring having the end curved in a hook-like way in the same direction of rotation of the ring concerned, whereas the fingers of the other ring are substantially straight and longer than those of the former ring, in operation a hooked finger and a straight finger coming simultaneously into contact with the rear wall of last box on the conveyor to thrust it out of the latter between the retaining members of the other conveyor as mentioned above, the longer finger initially bending the box to insert it partially between the retaining members and then the hooked end of the other finger entering action to complete the introduction of the box.

In order that the features of the invention may be better understood, an exemplary description will now be given of a preferred embodiment thereof, reference being had to the diagrammatical accompanying drawings, wherein:

FIG. 1 is a plan view which is illustrative of a conveyor constructed according to this invention;

FIG. 2 is an elevational view taken along the arrow A of FIG. 1, and

FIGS. from 3 to 6 are plan views which are illustrative of the several operational stages of the device which draws the boxes from the magazine and feeds them to the conveyor, respectively, and

FIGS. from 7 to 10 are plan views which respectively show the several operational stages of the device which draws the boxes from the conveyor to feed them to another conveyor.

Having now reference to FIGS. 1 and 2 of the drawings, the subject conveyor comprises a couple of chains as diagrammatically shown at 10 and 11 which can be driven to rotation in closed loop by a motive means 38: the chain 10 is rotated about three pinions for chain 12,

13 and 14, whereas the chain 11 is rotated about four chain pinions 15, 16, 17 and 18.

As it is clearly shown in FIG. 2, the pinions 14, 18 are keyed to their respective shaft 30, 31 and the shaft 30 is integral with the drive shaft 39 in an adjustable manner as to its angular setting, by means of a sleeve joint 40 having set screws 41. The drive from the shafts 39, 30 is transferred to shaft 31 through a drive transfer chain 42 which connects two gears 43, 44, the latter being respectively keyed to the shafts 30, 31.

To the chains 10, 11 there are affixed, respectively, a plurality of retaining members 19, 20, which are formed, each, by angular pieces which are mounted vertically; as can be clearly seen in FIG. 1 of the drawings, the angular irons are affixed to their respective chains and appropriately spaced apart from each other: in addition the faces of the angular irons of one chain, which are extended towards the longitudinal central axis of the conveyor, perpendicularly to the latter, lie on planes which are staggered through the thickness of an individual box 21 with respect to the corresponding faces of the angular irons of other chain.

Beneath the chains 10, 11 there are provided two sliding planes 45 for the boxes.

Near one end of the conveyor there is located a device which is adapted to draw the boxes 21 from a magazine as diagrammatically shown at 22, of the kind wherein the boxes are stored flat one against the others with the sidewall closed and the end limbs open: since these magazines are well known to those skilled in the art, they are not shown herein in detail. Said box-drawing device is generally indicated at 23 and is constructionally made up by an arm 24 which is pivoted at 25 so as to be rockable along an arc of 90 degrees between the position shown in solid line and that shown in dotted lines. The end of the arm 24 carries a suction cup 26 which is adapted to receive a negative pressure by any conventional suction means (not shown) via a suction duct 27.

At the end of the conveyor away of that on which the device 22 is positioned, another device is mounted, which is adapted to eject the boxes from the conveyor and to feed them onto another conveyor.

Such a device consists of two rings 28 and 29 which are keyed to their respective rotary shafts 30, 31, the latter integrally carrying the gears 14, 18. The ring 28 is equipped with three fingers 32 which are extended radially and are spaced apart from one another by even distances: each finger 32 has its end slightly curved in a direction which is opposite to the clockwise direction of rotation of the ring 28. Likewise, the ring 29 is equipped with three fingers 33 which extend radially and are evenly spaced apart from each other: each finger 33 has its end curved like a hook as at 34 in the same anticlockwise direction of rotation as the ring 29.

As clearly shown in the drawing, the fingers 32 are longer than the fingers 33 for the purpose which will be explained hereinafter.

The operation of the conveyor described above is as follows: the couple of chains 10, 11 is continually rotated, whereas the arm 24 is reciprocated between the two aforementioned positions synchronously with the rotation of the chains and more particularly with the position of the retaining members 19, 20.

At every operation cycle the arm 24 is brought from the position of FIG. 1 to the position of FIG. 3 where the suction cup 26, within which a negative pressure is

caused to obtain, sticks to the wall of the first box 21 of the stack as stored in the magazine 22. By so doing, during the return stroke of the arm 24, the first box is drawn by the suction cup (FIG. 4); as can be clearly seen in the drawings, the sidewall of the magazine 22 away of the arm 24 has an end retaining tab 35 which is curled towards the interior of the magazine; this tab 35 has the object of preventing more than one box from being drawn by the cup 26 at every operative cycle. The return of the arm 24 to the position of FIG. 1 causes the gradual opening of the box in the conventional way and as it is shown in FIGS. 4 and 5 until inserting the box, completely open, between two retaining members 19 and 20 (FIG. 6); as the box is inserted between the retaining members, the suction of the cup 26 is discontinued so as to allow the conveyor to draw freely away the box. The latter, after having undergone a processing step at the station diagrammatically shown at S, reaches the end of the conveyor which is opposite to the magazine 22: here, as shown in the close up of FIG. 7, the fingers 32, 33 of the rings 28 and 29, respectively, which are rotated in attunement with the conveyor enter contact with the rear wall of the box 21 to urge the box out of the conveyor, for example between retaining members 36 of another conveyor 37 which is moved perpendicularly to and in attunement with the former. The finger 32, which is longer than 33, first folds the box as shown in FIG. 8 to insert it partially between the retaining members 36: then the hook-like end 34 of the finger 33 completes the insertion of the box as shown in FIGS. 9 and 10.

With the conveyor made according to the invention it has become comparatively easy to synchronize the movement of the box drawing mechanism with the movement of the chains, even at high rotational speeds, virtually without any risk for the boxes not to enter their seating on the conveyor.

Another important advantage afforded by the conveyor according to the invention is that to preset it to the operation consistently with the box thickness, it is merely required that the angular setting of the shaft 30 be adjusted, said shaft carrying the gear 14, with respect to the driving shaft 39 in such a way as to displace the chain 10 with respect to 11 in order more or less to stagger the retaining members 19, 20 thereon.

The conveyor according to the invention has proven to be particularly suitable to be employed together with machines for applying pouring spouts to a wall of a container: the processing station S can comprise one of said machines and the pouring spouts are diagrammatically shown at 46 in the drawings.

While an embodiment of the invention has been shown and described, those skilled in the art will understand that modifications and changes can be introduced therein; for example the device for drawings the boxes from the magazine could be of another type, and the rings equipped with fingers could be dispensed with, without thereby changing the basic idea of the invention and its scope as defined by the appended claims only.

What is claimed is:

1. In a conveyor system for cardboard boxes intended to have a parallelepipedal final shape including a magazine in which the boxes are stored flat one against the other with the sidewall closed and the end limbs open and a device adapted to draw the boxes from said magazine and to feed them onto a conveyor opened in their

parallelepipedal final shape, the improvement comprising said conveyor which includes at least one flexible member driven in a closed loop so as to define two laps parallel to one another and spaced apart through a distance equal to the box width, a plurality of retaining members affixed to and properly spaced apart from each other on said flexible member, adjustable motive drive means for continuously moving said flexible member so that said parallel laps are advanced in the same direction and synchronously with respect to each other with the retaining members on said parallel laps staggered to correspond to the thickness of a box by defining a plurality of couples of confronting shoulders adapted to receive therebetween a box which will abut each shoulder couple in correspondence with two diagonally opposite edges of said box.

2. In a conveyor system in accordance with claim 1, wherein said flexible member comprises two endless chains, each of which is driven in a closed loop by a single adjustable motive means, and said parallel laps are defined by parallel portions of said chains.

3. In a conveyor system in accordance with claim 1, wherein said retaining members are each formed by an angular piece which is arranged vertically on said flexible member.

4. In a conveyor system in accordance with claim 2, wherein said adjustable motive means includes a rotatable drive shaft, a first rotatable driven shaft, flexible coupling means between said drive shaft and first driven shaft for adjusting the angular relationship of said drive and first driven shafts, a first sprocket on said first driven shaft operatively connected to one of said endless chains, a second driven shaft substantially parallel to said first driven shaft, a second sprocket on said second driven shaft operatively connected to the other of said endless chains, and drive transfer means between said first and second driven shafts whereby rotational motion of said first driven shaft is imparted to said second driven shaft and said chains can be moved in synchronization, the angular relationship between said first and second driven shafts being adjustable through said flexible coupling means to adjust and further stagger the distance between the retaining members on said chains to compensate for different box thicknesses.

5. In a conveyor system for cardboard boxes intended to have a parallelepipedal final shape including a magazine in which the boxes are stored flat one against the other with the sidewall closed and the end limbs open and a device adapted to draw the boxes from said magazine and to feed them onto a conveyor opened in their parallelepipedal final shape, the improvement comprising said conveyor which includes at least one flexible member driven in a closed loop so as to define two laps parallel to one another and spaced apart through a distance equal to the box width, a plurality of retaining members affixed to and properly spaced apart from each other on said flexible member, adjustable motive drive means for continuously moving said flexible member so that said parallel laps are advanced in the

60

same direction and synchronously with respect to each other with the retaining members on said parallel laps staggered to correspond to the thickness of a box by defining a plurality of couples of confronting shoulders adapted to receive therebetween a box which will abut each shoulder couple in correspondence with two diagonally opposite edges of said box, and means for removing said boxes from the two parallel laps of said flexible member to insert them between retaining members of another conveyor, said means including first and second rings rotated at the same speed in opposite directions and each being equipped with a plurality of radially extending fingers which are spaced apart from each other in an equal manner, the fingers of the first ring having a hook-like curved end extending in the same direction of rotation of the ring, the fingers of said second ring being substantially straight and longer, so that in operation a hook-like finger and a straight finger come simultaneously in contact with the rear wall of a box on the flexible member to thrust the box therefrom between the retaining members of the other conveyor, the longer straight finger first folding the box to insert it partially between the retaining members, then the hooked end of the other shorter finger entering into the action to complete the insertion of the box.

6. In a conveyor system in accordance with claim 5, wherein said flexible member comprises two endless chains, each of which is driven in a closed loop by a single adjustable motive means, and said parallel laps are defined by parallel portions of said chains.

7. In a conveyor system in accordance with claim 5, wherein said retaining members are each formed by an angular piece which is arranged vertically on said flexible member.

8. In a conveyor system in accordance with claim 6, wherein said adjustable motive means includes a rotatable drive shaft, a first rotatable driven shaft, flexible coupling means between said drive shaft and first driven shaft for adjusting the angular relationship of said drive and first driven shafts, a first sprocket on said first driven shaft operatively connected to one of said endless chains, a second driven shaft substantially parallel to said first driven shaft, a second sprocket on said second driven shaft operatively connected to the other of said endless chains, and drive transfer means between said first and second driven shafts whereby rotational motion of said first driven shaft is imparted to said second driven shaft and said chains can be moved in synchronization, the angular relationship between said first and second driven shafts also being adjustable through said flexible coupling means to adjust and further stagger the distance between the retaining members on said chains to compensate for different box thicknesses.

9. In a conveyor system in accordance with claim 7, wherein said first ring is keyed to said second driven shaft and said second ring is keyed to said first driven shaft.
